UNITED STATES PATENT OFFICE.

PAUL BOST, OF HOHEN-NEUENDORF, GERMANY.

CORD FOR SURGICAL LIGATURES.

No Drawing. Application filed July 16, 1927, Serial No. 206,377, and in Germany July 15, 1926.

Absorbable surgical cords were heretofore mostly made from twisted animal guts. The disadvantage of this element is that the same is not only not free from germs but often 5 very strongly infected and therefore it is extremely difficult to sterilize such cords. Also such cords can only be made of a limited length. If longer cords are needed they must be knotted together and such knots are 10 a hindrance.

In the market guts are scant and expensive. Therefore a more complete and cheaper surgical sewing material has been for a long time very much wanted.

15 It is known that animal sinews are used for textile purposes for instance for the manufacture of felt. Such sinews are extraordinarily breakable and brittle and can not be spun into long strings, such as are needed for 20 surgical strings.

The defects of the known chirurgical strings are removed by the present improvement thereby that from the very beginning fibres are used, which are gained from the 25 possibly fresh flesh of the muscle which is especially suitable therefor owing to its poverty of germs.

These fibres and textures are to be manufactured in the known manner but from the 30 very beginning under steril conditions, so that firstly the blood serum is withdrawn from the muscle flesh by washing out or in any other suitable manner and that then the element material during its preparation undergoes sterilizing and hardening processes— 35 for instance with formaline, chromic acid, solutions of iodine or other ingredients—that furthermore during the spinning and weav-

ing the poverty of germs of the element material is preserved and finally the finished 40 spinning or texture is made ready for use by a final sterilization taking place hereafter or at any desired time. For instance one firstly ungreases by means of benzinoform the flesh fibres obtained under the strictest 45 guarding of the poverty of germs present from the very beginning, then sterilizes the same in a weak solution of formaline and tans the same. After the drying, the fibres are spun, 50 during which process the transfer of germs must possibly be prevented, and the finished textures are again submitted to a suitable sterilizing process which makes the same absolutely free from germs. The freeing from germs can be effected by chemicals, by the 55 effect of heat or in any other way. The spinnings or textures can be used vulcanized or not vulcanized. Also the spun fibre cords can be twisted together to stronger cords.

The advantages of the described cord in 60 opposition to the heretofore used cord are principally

- (1) Reliable immunity from germs.
- (2) Manufacture in suitable length without knots.
- (3) Manufacture of any necessary, and uniform, strength of cord.
- (4) Sufficient and uniform strength of pulling, flexibility, and cheapness.

Claim—

Cords for surgical purposes made in a known manner from the fresh flesh of the muscles.

In testimony whereof I have signed my name to this specification.

PAUL BOST.
